UNITED STATES PATENT OFFICE

170,852

DRILL DISPLAY UNIT OR SIMILAR ARTICLE

Laurence H. Drohman, St. Paul, Minn.

Application October 15, 1952, Serial No. 21,841

Term of patent 14 years

(Cl. D80—9)

To all whom it may concern:

Be it known that I, Laurence H. Drohman, a citizen of the United States, residing at St. Paul, in the county of Ramsey and State of Minnesota, have invented a new, original, and ornamental Design for a Drill Display Unit or Similar Article, of which the following is a specification, reference being had to the accompanying drawing, forming part thereof in which:

Fig. 1 is a front perspective view of the drill display unit or similar article embodying my new design; and

Fig. 2 is a plan view thereof.

The broken line showing is for illustration purposes only.

I claim:

The ornamental design for a drill display unit or similar article, substantially as shown and described.

LAURENCE H. DROHMAN.
